DESIGN FOR A BROOCH OR SIMILAR ARTICLE

Sara Roberts Burke, Staten Island, N. Y.

Application January 15, 1941, Serial No. 98,236

Term of patent 3½ years

To the Commissioner of Patents:

Be it known that I, Sara Roberts Burke, a citizen of the United States of America, residing at 207 Daniel Low Terrace, Staten Island, in the county of Richmond and State of New York, have invented a new, original, and ornamental Design for a Brooch or Similar Article, of which the following is a specification.

In the accompany drawing:

Figure 4 is a section, taken on lines 4—4 of Fig. 2.

I claim as my invention:

The ornamental design for a brooch or similar article, substantially as shown.

SARA ROBERTS BURKE.
